UNITED STATES PATENT OFFICE.

WALTER M. SOMMER, OF NEW YORK, N. Y., ASSIGNOR OF ONE-HALF TO
OSCAR HEYMAN & COMPANY, OF NEW YORK, N. Y., A COPARTNER-SHIP.

DESIGN FOR A BOTTLE.

No. 37,580.

Specification for Design.

Patented Oct. 24, 1905.

Application filed August 16, 1905. Serial No. 274,478. Term of patent 7 years.

To all whom it may concern:

Be it known that I, WALTER M. SOMMER, a citizen of the United States, residing in the borough of Brooklyn, city of New York, county of Kings, and State of New York, have invented a new, original, and ornamental Design for a Bottle, of which the following is a specification, reference being had to the accompanying drawing, forming a part thereof.

The figure is a perspective view showing my new design.

I claim—

The ornamental design for a bottle as shown.

WALTER M. SOMMER.
